WALL BED

Edward E. Woller, Kenosha, Wis., assignor to
Simmons Company, Kenosha, Wis., a corpora-
tion of Delaware

Application May 16, 1946, Serial No. 670,167

9 Claims. (Cl. 5—160)

1

This invention relates to folding beds of the type which are adapted to be swung to a vertical position for concealment within a wall recess when not in use. Such structures usually include a linkage for movably supporting the head end of the bed within the wall recess and a pair of foldable legs for supporting the foot end of the bed when it is lowered into the room.

The main objects of this invention are to provide an improved form of wall bed which may be concealed within a wall recess of minimum depth and which is particularly adapted for use on railroad Pullman cars and on ships; to provide an improved linkage for movably supporting the head end of the bed within the wall recess; to provide improved automatically actuated means for extending the legs when the bed is lowered and for folding the legs against the bed when the bed is raised to its concealed position; to provide an improved wall panel forming a door for closing the recess to conceal the bed when the bed is in folded position; to provide improved means for attaching the panel to the bed; to provide improved counter-balancing means to facilitate raising and lowering of the bed; and to provide a simple and durable wall bed of this type which will accommodate an innerspring mattress of standard thickness.

An illustrative embodiment of this invention is shown in the accompanying drawings wherein:

Figure 1 is a fragmentary perspective view of a wall and recess showing the improved bed in partly lowered position.

Figure 2 is a view similar to Figure 1, but showing the bed lowered to horizontal position.

Figure 3 is a fragmentary plan view of the inner side of the upper end of the wall panel showing the latch mechanism for locking the panel to the frame of the recess.

Figure 4 is a side elevation, partly broken away and partly in section, showing the bed opened to horizontal position.

Figure 5 is an enlarged detail in section of the counter-balancing means.

Figures 6 and 7 are enlarged fragmentary end elevations of the bed, taken from the left and right, respectively, of Figure 4, showing the mechanism for automatically folding and extending the supporting legs.

Figure 8 is an enlarged fragmentary side elevation of the bed, showing the linkage which connects the panel to the head end of the bed.

Figure 9 is an enlarged transverse section of the panel latch operating mechanism, the view being taken on the line 9—9 of Figure 3.

2

As shown in the drawings, the improved structure includes a bed 1 movably supported in an upright, rectangular frame 2 which defines a recess 3 in the wall 4 of a home, ship, railway car, automobile trailer, or other conveyance.

The bed 1 may be of the standard full size or of any of the smaller sizes. In the form illustrated, it includes a mattress 5 supported on a flat spring structure 6 which is suspended in a frame 7 to which the mattress is secured by suitable straps 8.

The frame 7 comprises a pair of tubular members 9 and 10 of rectangular shape arranged in spaced relation and secured together by a plurality of struts 11. At the sides of the frame, the member 9 is bent to form a U-shaped brace 12 which is spot welded to the member 10.

The bed is suspended by a pair of L-shaped links 13 having their upper ends pivotally secured to the recess frame 2 by pivots 14 engaging slots 15 in the frame. The lower, forwardly projecting ends of the links 13 are pivotally connected to the bed frame by pins 16 which engage plates 17 extending between the members 9 and 10 of the frame 7.

When the bed is in open position, as shown in Figures 2 and 4, the outer end thereof is supported on a pair of foldable legs 18 which are pivotally secured to the frame member 10 by pins 19.

The automatic actuating mechanism for the legs includes a pair of longitudinally extending rods 20 rotatably supported in the frame member 10 at respectively opposite sides thereof. Rigidly mounted on the rods 20 are arms 21, the lower ends of which are pivotally secured to the legs 18 by short links 22 whereby the legs may be folded and extended by the rotation of the rods.

Rotation of the rods 20 is effected by the mechanism illustrated in Figure 6. The rear end of each of the rods 20 has fixed thereon an arm 23 pivotally connected to a link 24 which in turn is pivotally connected to a lever 25 which is pivotally supported on a plate 26 of the bed frame. The outer end of the lever 25 coacts with a stop 27 on the recess frame 2 so that, when the inner end of the bed moves upwardly during the bed-opening operation, the link 24 moves downwardly to rotate the arm 23 and its rod 20, thereby causing the arm 21 at the forward end of the rod to unfold the leg 18 outwardly and downwardly into bed-supporting position. Connected to the legs 18 and the frame member 10 are springs 28 which normally urge the legs inwardly toward their folded positions. Upon closing the bed, the inner

end of the bed moves downwardly so as to swing the links 25 away from the stop 27 to permit the springs 28 to retract the legs 18.

To facilitate movement of the bed to its closed and open positions, the structure includes the counter-balancing mechanism illustrated in Figures 4 and 5. This mechanism includes a horizontal shaft 29 which extends through the rear tube 30 of the bed frame member 9. The shaft 29 is journalled in ball bearings 31 supported in journal boxes 32 which are secured to the ends of the tube 30 by clamping rings 33. The journal boxes 32 and rings 33 are clamped together by screws 33a. Mounted on the shaft 29 is a series of short sleeves 34 embraced by a helical spring 35. One end of this spring is anchored to one of the journal boxes 32 and the other end thereof is secured to a sleeve 36 which is fixed on the shaft 29.

Fixed on the ends of the shaft 29 are pinions 37, which mesh with vertically disposed racks 38 mounted on respectively opposite sides of the recess frame 2 so that when the bed is raised and lowered, the shaft 29 is rotated. The arrangement is such that, when the bed is opened, the head end rises so as to rotate the shaft 29 in a direction which will contract the spring 35 and therefore the spring, having a tendency to unwind, will assist in raising the bed to the vertical position.

Also mounted on the ends of the shaft 29 are discs 39 which ride between a pair of spaced guide rails 40, 41 for securing the pinions 37 in operative engagement with the racks 38.

To prevent the bed sheets from becoming entangled in the mechanism in the space behind the bed frame, a thin sheet metal cover plate 42 overlies the tube 30. Its rear edge is fixed on a rod 43 which is rotatably supported in the side members of the recess frame 2. Fixed on the rod 43 are arms 44 which are pivotally connected to the lower ends of vertical links 45. The upper ends of these links 45 are connected to plates 46 which are pivotally supported on pins 47. A link 48 operatively connects each of the plates 46 with the adjacent L-shaped supporting link 13 so that, when the link 13 moves rearwardly as the bed is raised to vertical position, the link 45 is lifted so as to swing the cover plate 42 rearwardly in contact with the face of the mattress.

When the bed is folded to vertical position, it is concealed within the wall recess by an improved door panel 49 which is sufficiently large to completely fill the opening. In order to permit folding and unfolding of the legs 18, it is necessary to support the panel by means which will permit a longitudinal shifting of the panel relative to the bed frame. This is accomplished by a pair of links 50, 51 located at each side of the bed for pivotally connecting the panel to the frame member 10. Longitudinal shifting of the panel is effected by the links 13 which are operatively connected to the links 51 by links 52 having slots 53 for receiving pins 54 on the supporting links 13.

The construction is such that, in lowering the bed to horizontal position, the pins 54 engage the links 52 at the lower ends of the slots 53 for shifting the panel rearwardly so as to permit unfolding of the legs 18. In raising the bed to its concealed position, the pins 54 lift the links 52 and 51 so as to shift the panel upwardly for completely closing the wall recess. In this manner, the panel is shifted positively in either direction

by the link 52, although it will be understood that by properly positioning the links 50 and 51 on the frame member 10, the panel 49 may be shifted sufficiently rearwardly by the force of gravity alone to clear the legs 18, in which case, the link 52 may function merely to lift the panel into recess-closing position as the bed is stowed.

Formed on the links 51 are rearwardly projecting shoulders 55 which are adapted to engage lugs 56 on the frame member 10 for securing the panel against any swinging action when the bed is open.

Mounted on the inner face of the door panel, is a locking mechanism comprising a pair of latch bolts 57 slidably mounted in guides 58 and adapted for engagement with keepers 59 at the sides of the recess frame 2. The latch bolts are retracted by a pair of links 60 pivotally connected to a rotary disc 61 having a square shaft 62 which is rotatably mounted in a bearing 63 supported in a boss 64 on a cup-shaped member 65 which is seated in an opening 66 of the panel. The shaft 62 is rotated for retracting by latch bolts by means of a handle 67 having a hub 68 provided with a square opening 69 for receiving the shaft 62. Located within the hub 68 is a helical spring 70 which bears between the inner end of the hub and a headed screw 71 on the outer end of the shaft so as to normally hold the handle 67 within the cup 65. The shaft 62 is secured against accidental turning by means of a pin 72 projecting from the hub 68 into a recess 73 of the boss 64. To open the panel door 49, the handle 67 is pulled outwardly against the action of the spring 70 until the pin 72 has been withdrawn from the recess 73, whereupon the handle may be turned for retracting the latch bolts 57.

When the latch bolts 57 are retracted, the bed may be lowered to the horizontal position. During the lowering of the bed, the links 13, 52 and 51 shift the panel 49 rearwardly and the legs 18 are extended by the rotation of the rods 20 through the action of the members 23, 24, 25, and 27. Also, during the lowering of the bed to horizontal position, the pinions 37 riding on the racks 38 wind the helical spring 35 so as to counterbalance the weight of the bed to facilitate closing of the bed.

To close the bed, its foot end is raised thereby automatically folding the legs 18 and raising the panel 49 into position to completely cover the wall recess for concealing the bed.

Although but one specific embodiment of this invention has been herein shown and described, it will be understood that details of the construction shown may be altered without departing from the spirit of the invention as defined by the following claims.

60 I claim:

1. A bed comprising a vertical wall cabinet having an opening, a bed frame, mounting means for supporting one end of said frame on a vertically movable fulcrum within said cabinet whereby said frame may be shifted to a vertical position within said cabinet or extended through said opening to horizontal bed position, a pair of foldable legs hinged on the outer end of said frame on axes disposed longitudinally of said frame, a pair of rotatable rods extending longitudinally of said frame and operatively connected to said legs, and means actuated through the movement of said frame for rotating said rods to fold and extend said legs.

75 2. A bed comprising a vertical wall cabinet

having an opening, a bed frame, mounting means for supporting one end of said frame on a vertically movable fulcrum within said cabinet whereby said frame may be shifted to a vertical position within said cabinet or extended through said opening to horizontal bed position, a pair of foldable legs hinged on the outer end of said frame on axes disposed longitudinally of said frame whereby said legs are swingable in a vertical plane transverse to said frame, automatically actuated means for folding and extending said legs through the movement of said frame, and a door panel carried by said frame and movable thereby into position to close said opening for concealing said frame and legs when the bed is disposed vertically within said cabinet, said panel being shiftable longitudinally relative to said frame to uncover said legs when said frame is moved to horizontal position.

3. A bed comprising a vertical wall cabinet having an opening, a bed frame, mounting means for pivotally supporting one end of said frame within said cabinet whereby said frame may be shifted from a vertical position within said cabinet through said opening to a horizontally extended bed position, a foldable leg hinged on the outer end of said frame, a door panel disposed beneath said frame when said frame is horizontally extended and movable therewith into position to close said opening for concealing said frame and leg when said frame is disposed vertically within said cabinet, links suspending said panel from said frame whereby said panel is shiftable longitudinally of said frame to permit the unfolding of said leg when said frame is horizontally extended, and means actuated through the movement of said frame from said vertical position to said horizontally extended position for shifting said panel to uncover said leg to permit its unfolding, said last-mentioned means being operable by the shifting of said frame from said horizontally extended position to said vertical position to shift said panel into a position to cover said frame and leg and close said opening.

4. A bed comprising a vertical wall cabinet having an opening for stowing a bed frame in vertically disposed position, a vertically disposed guideway in said cabinet opening having a gear rack along one face thereof, a bed frame, a pair of links supporting said bed frame on said cabinet to permit a 90-degree swinging of said frame between said vertically-disposed stowed position and a horizontally-extended open position, a shaft journaled on the inner end of said frame and mounting a gear meshing with said rack to traverse the length thereof during the 90-degree swinging of said bed frame, and a torsion spring embracing said shaft and having its opposite ends anchored respectively to said shaft and said frame whereby the travel of said gear upwardly along said rack tensions said spring so as to counterbalance the weight of said frame moving toward its horizontally-disposed position.

5. A bed comprising a vertical wall cabinet having an opening, a bed frame, mounting means for supporting one end of said frame on a vertically movable fulcrum within said cabinet whereby said frame may be shifted to a vertical position within said cabinet or extended through said opening to horizontal bed position, a pair of foldable legs hinged on the outer end of said frame on axes disposed longitudinally of said frame whereby said legs are swingable in a vertical plane transverse to said frame, automatically

ly-actuated means for folding and extending said legs through the movement of said frame, a door panel carried by said frame, means connecting said panel to said mounting means so as to be actuated by the swinging of said frame to automatically effect the opposite shifting of said panel longitudinally of said frame to remove said panel from the path of said legs and thereby permit the transverse vertical movement of said legs as said frame moves into and out of its horizontal bed position.

6. A bed comprising a vertical wall cabinet having an opening for stowing a bed frame in vertically-disposed position, a vertically disposed guideway in said cabinet opening, a bed frame, guide means on said frame confined for vertical movement in said guideway, a pair of links suspending said bed frame from said cabinet to permit a 90-degree swinging of said frame between its vertically-disposed stowed position and a horizontally-extended open position, said links having their upper ends fulcrumed within said cabinet opening and their lower ends pivoted to said frame forwardly of the inner end thereof a distance approximating the vertical travel of said guide means in said guideway, legs mounted at the outer end of said frame and shiftable into and out of position to support the outer end of said frame in its horizontally-disposed position, a door panel for closing the opening in said cabinet, a plurality of links suspending said door panel on said frame to permit a shifting of said panel longitudinally of said frame, and a link lever connecting said frame suspension links with one of said door panel suspension links whereby the swinging of said frame on its suspension links automatically effects a shifting of said door panel longitudinally of said frame to uncover said legs when said frame is in its horizontal position.

7. A concealed bed arrangement comprising a bed bottom unit adapted to be pivotally supported at one of its ends in a wall recess and shiftable from a vertical position in said recess to a horizontally extended bed position, said bed bottom unit including a mattress-supporting frame, a folding leg hinged to the outer end of said frame, and a closure panel for concealing said frame and leg in said recess, said panel and frame being relatively shiftable to uncover said leg when the unit is in horizontal position whereby said leg may be unfolded, and means operable by the shifting of said unit from said horizontally extended position into said recess to effect relative longitudinal movement of said panel and frame into a position to cover said frame and leg and close said recess.

8. A concealed bed arrangement comprising a mattress supporting frame adapted to be pivotally supported at one of its ends in a wall recess and shiftable from a vertical position in said recess to a horizontally extended bed position, a foldable leg hinged on the outer end of said frame, a door panel disposed beneath said frame when said frame is horizontally extended and movable therewith into position to close said recess for concealing said frame and leg when said frame occupies said vertical position, links suspending said panel from said frame whereby said panel is shiftable relative to said frame to uncover said leg when said panel is horizontally extended whereby said leg may be unfolded, and means operable by the shifting of said frame from said horizontally extended position into said recess to shift said panel relative to said frame to cover said frame and leg and close said recess.

9. A concealed bed arrangement comprising a mattress supporting frame, mounting means adapted to pivotally support said frame at one of its ends in a wall recess whereby said frame is shiftable from a vertical position within said recess to a horizontal bed position, a foldable leg hinged on the outer end of said frame, a door panel disposed beneath said frame when said frame is horizontally extended and movable therewith into position to close said recess for concealing said frame and leg when said frame occupies said vertical position, links suspending said panel from said frame whereby said panel is shiftable relative to said frame toward said recess to uncover said leg when said frame is horizontally extended whereby said leg may be unfolded, and a connection between at least one of said links and said mounting means whereby the movement of said frame from its horizontal position into said recess is effective to shift said panel relative to said frame thereby to cover said frame and leg and to close said recess.
